(57) **CLAIM**

The ornamental design for a sports ball rack, as shown and described.

DESCRIPTION

FIG. 1 is a perspective view of a sports ball rack showing my new design;

FIG. 2 is a front elevational view thereof;

FIG. 3 is a rear elevational view thereof;

FIG. 4 is a side elevational view of one side thereof;
FIG. 5 is a side elevational view of a side opposite that shown in FIG. 4;

FIG. 6 is a top plan view thereof; and

FIG. 7 is a bottom plan view thereof.

FIG. 8 is a perspective view of another embodiment of a sports ball rack showing my new design;

FIG. 9 is a front elevational view thereof;

FIG. 10 is a rear elevational view thereof;

FIG. 11 is a side elevational view of one side thereof;

FIG. 12 is a side elevational view of a side opposite that shown in FIG. 11;

FIG. 13 is a top plan view thereof; and,

FIG. 14 is a bottom plan view thereof.
